SCREEN STRUCTURE

David F. Newman, Rockville Centre, N. Y., assignor to Trans-Lux Corporation, a corporation of Delaware

Application April 17, 1936, Serial No. 74,913

2 Claims. (Cl. 88—24)

My invention relates to a composite structure utilizable, if desired, solely as a screen for rear projection purposes. My invention also has reference to a composite structure serving, if desired, in a dual manner, i. e., as a rear projection screen and in connection with or as a part of a sound reproducing system. It shall be understood that references in this specification and in the appended claims to a "screen" or "projection screen" shall be understood as generically comprehending a screen utilizable solely for projection purposes or in connection with a sound reproducing system as stated.

In accordance with my invention, a screen or composite structure of the character stated comprises screen-forming material having associated, incorporated, or combined therewith fabric of a character not heretofore used in the screen art and possessing advantages over those fabrics which have been used in association with screen-forming material.

Further objects, advantages and characteristics of my invention will become apparent from the following description.

My invention resides in the screen, composite structure, features and arrangements of the character hereinafter described and claimed.

This application is a continuation in part of my prior application Serial No. 512,533, filed January 31, 1931, renewed September 1, 1933.

On the accompanying drawing:

Figure 1 is a view illustrating fabric of a character heretofore used in association with screen-forming material;

Fig. 2 is an enlarged plan view illustrating a section of a screen as constructed in accordance with my invention; and

Fig. 3 is a vertical sectional view taken substantially on the line 3—3 of Fig. 2 looking in the direction of the arrows.

My invention relates particularly although not necessarily to screens or composite structures of the character stated which comprise translucent screen-forming or body material formed from gelatine and glycerine or other material as may be desirable and with which there is associated or incorporated a sheet of fabric of a type not heretofore used in the screen art, such screens being adapted particularly for rear projection.

More particularly, the aforesaid body material may be of a character known to those skilled in the art. For example, such body material may correspond more or less with that disclosed in U. S. Letters Patent No. 1,151,502, No. 1,231,727,

or No. 1,980,285, it being understood, however, that the use of some of the agents mentioned in said Letters Patent is optional depending upon the use for which the projection screen is intended. As understood in the art, the aforesaid body material may be so produced that it exists as a mass of viscous material.

From the viscous material thus obtained, a sheet-like screen or screen structure of suitable thickness may be produced in any suitable manner. Preferably, this is accomplished by a molding operation, a suitable matrix table embodying a plane surface of suitable material and extent or area being utilized for the reception of the mixture. The surface of the table should be bordered by a retaining wall of a height substantially equal to the thickness of the screen or composite structure to be produced and said table should be heated to suitable extent, preferably within a range somewhat below the temperature of the aforesaid mixture.

After the matrix table has been brought to such suitable temperature conditions as stated and with the aforesaid mixture in proper condition, the latter should be poured on or applied to the table, preferably until it slightly overflows the bordering wall thereof. The excess material should now be removed, as by application of a straight edge to the aforesaid retaining wall.

It has been proposed, in accordance with the disclosure of Troeger U. S. Letters Patent No. 1,216,380 to strengthen a screen with strands and, more particularly, these strands may be of silken thread. Further and in accordance with the disclosure of U. S. Letters Patent No. 1,672,656 to Arthur C. Payne, it is known that there may be associated with screen-forming material a crinkly fabric and, more particularly, one of irregular weave, as georgette crepe, such as is shown at G on Fig. 1 of the drawing.

Primarily, fabrics, as aforesaid, are utilized so as to prevent or impede sag of the screen when it is subjected to high and/or humid temperature conditions. A fabric such as georgette crepe is reasonably satisfactory for the intended purpose but this does not hold true under all conditions and circumstances. Such a fabric is of the interlaced strand type and, if the width thereof exceeds 76 inches ordinarily or 92 inches as the usual highest limit, a sort of selvage as at a, Fig. 1, is formed by the weaving machinery when the width attains the value stated above, this selvage extending longitudinally of the fabric whereby the latter in a lengthwise zone is nor-

uniform as compared with the more uniform material at opposite sides of said zone. This selavage is not a true one inasmuch as it consists merely of an accumulation or closer grouping of the lengthwise strands in the aforesaid lengthwise zone, it having proven impractical to overcome this condition due to mechanical limitations of commercial weaving machinery if the fabric widths exceed those stated above.

10 Aside from the primary defect noted above, interlaced strand fabric such as georgette crepe is objectionable in a number of more or less secondary respects.

Thus, as indicated at *b*, Fig. 1, the fabric *G* may be more or less irregular both longitudinally and transversely, such defects arising for a variety of reasons such, for example, as the improper handling or placement of the delicate strands, the fact that such strands are apt to vary in diameter in different lengthwise zones, etc.

Further, as indicated at *b1*, Fig. 1, commercially woven silk fabric is characterized by non-uniformity. More particularly, this non-uniform condition is present both lengthwise and crosswise of the fabric and appears as a series of alternating light and dark bands of varying widths.

For ordinary non-screen uses, artificial fillers may be so associated with the fabric as to cause it to be of substantially uniform appearance, such 30 artificial fillers rendering minor selvages and other non-uniform conditions practically unnoticeable. However, as known to the art and partly as hereinafter stated, fabrics to be used in the production of projection screens of the 35 character herein described should be free from such artificial fillers and should also be as free as possible of inherent foreign matter such as gums, resins, etc. Under such conditions, the association with screen-forming material, as de- 40 scribed above, of an irregular or non-uniform fabric such, for example, as of the general character shown in Fig. 1 causes the screen, during projection, to be of non-uniform appearance since the selvaged and other irregular or non- 45 uniform areas are dark and there is a marked contrast between them and adjacent more truly uniform areas. This contrasting appearance between adjacent screen areas, of course, is ob- jective.

50 I have determined that, as a substitute for fabric of the type described above, i. e., fabric of the interlaced strand type wherein the warp and filling threads are disposed at right angles and are not twisted around each other, there may 55 advantageously be utilized knit fabric preferably formed from silk strands as fabricated, for example, on any suitable knitting machine. Knit fabric as produced by such machines may be dimensionally larger, as regards width and length, 60 than is required for rear projection screens, said fabric being of generally uniform character throughout the area thereof in the sense that there is little or no selavage or other non-uniformity such as indicated at *a*, *b* and *b1* of the fabric 65 *G* of Fig. 1. In this specification and in the appended claims, the term "uniform", when used in a descriptive sense as regards the knit fabric, shall be understood as referring solely to the 70 omission of the above noted selavage or other non-uniformity from said knit fabric. Accordingly, when the dimensions of a desired screen are relatively large, a section of the above described knit fabric may be associated with the body material 75 to thereby produce a screen which, during the

projection operation, does not exhibit non-uniformities such as exist in the fabric *G*.

Accordingly, to construct the screen of my invention, a suitable sheet of knit fabric, such as indicated at *K*, Fig. 2, from which foreign matter such as gums, resins, etc., has been suitably removed should be stretched on a frame having an opening of such extent that it fits snugly around the aforesaid retaining wall of the matrix table. As shown, any given section of this knit fabric *K* is formed from strands *s* disposed in looping relation as at *t*, this being customary in the knitting art.

After the excess screen-forming material has been removed from the matrix table as stated 15 above, the sheet of knit fabric *K* is suitably lowered toward and into engagement with the upper surface of the material on the matrix table, care being taken to avoid entrapment of air between the knit fabric sheet and the viscous material. 20 In so doing, the frame holding said knit fabric sheet comes into position around the aforesaid retaining wall of the matrix table, and thereupon the knit fabric sheet sinks into or becomes associated with the viscous material. At this time, 25 application of heat to the matrix table should be discontinued and, after a suitable cooling period, as two or three hours, has elapsed, a knife should be passed between the frame holding the knit fabric sheet and the retaining wall of the matrix 30 table to sever said sheet from its frame. Thereupon, the molded screen, now translucent to a desired degree, may be removed from the matrix table in any suitable manner. As indicated in Figs. 2 and 3, the operation thus described yields 35 a screen which comprises a sheet of translucent material *M* with which is combined the aforesaid sheet of knit fabric *K*.

Thereafter, the edges of the screen should be suitably bound, as by canvas strips or the like adhesively or otherwise suitably secured thereto, the strips preferably being provided with eyelets. When the screen is installed for use, a suitable frame should be provided and the screen positioned therein under a suitable degree of tension, 45 as by rope passing through the eyelets and engaging the frame.

A screen constructed in accordance with my invention is durable and functions in an entirely satisfactory way for the display of representations to an audience. The knit fabric *K* functions in a desirable manner to reinforce the screen and to thereby prevent or impede the aforesaid screen sag. In this connection, it seems that knit fabric, probably due to the different 55 mesh characteristics, is more readily or better associatable with the viscous screen-forming material than are the interlaced strand fabrics heretofore used in this connection. At the same time, the knit fabric is highly satisfactory from 60 the projection viewpoint. This follows because knit fabric of the type described is of uniform character throughout and, as a result, the screen, during projection, is not of streaked or other irregular appearance. In addition, it has been 65 determined in practice that, in an unpredictable manner and for an unknown reason, sections of a sheet of interlaced strand fabric *G* do not always amalgamate or sink into the translucent body material when said fabric sheet is lowered into 70 engagement therewith. This defect, when it occurs, is noticeable to a marked extent during the projection operation and renders the screen unsatisfactory for use. Experience has demonstrated, at least for screens of small dimensions, 75

that the use of knit fabric K overcomes the difficulty last noted. That is, such knit fabric K, throughout the entire area thereof, amalgamates or sinks into the viscous body material to thereby produce a screen of highly desirable character from the projection viewpoint.

As hereinbefore stated, my invention has reference to a rear projection screen which, as well understood in the art, is disposed between the projector and those viewing the images on said screen. With a rear projection screen, the light passes through the screen during the projection operation and, therefore, any imperfections such as those existing in the sheet of interlaced strand fabric G are in the visible field and hence objectionable. However, when the screen comprises a sheet of knit fabric K, in lieu of the interlaced strand fabric G, the screen throughout the entire area thereof is of regular, uniform appearance, 20 this, of course, being highly desirable.

It is well known in the art that interlaced strand fabric of the character shown in Fig. 1 is one in which the warp and filling threads are disposed at right angles to each other, the filling 25 threads crossing the warp threads in non-twisted relation such, for example, as illustrated in the aforesaid Letters Patent No. 1,231,727. With a section of knit fabric as herein described, the strands are disposed in interlooping relation as 30 well understood in the knit fabric art. It shall be understood that my invention as defined in the appended claims is limited to a translucent screen which is properly light diffusive, as determined by the light-diffusive agent and the fabric sheet, 35 for rear projection practice and which comprises

a sheet of knit fabric of the character just described.

While the invention has been described with respect to a certain particular preferred example which gives satisfactory results, it will be understood by those skilled in the art after understanding the invention, that various changes and modifications may be made without departing from the spirit and scope of the invention and it is intended therefore in the appended claims to 10 cover all such changes and modifications.

What is claimed as new and desired to be secured by Letters Patent is:

1. In a projection screen, a sheet-like body of translucent material, and a sheet of uniform knit 15 fabric combined with said body of translucent material, said translucent material and said sheet of knit fabric cooperating to form a screen properly light-diffusive for rear projection practice, a substantial amount of light passing through 20 said knit fabric and the translucent material when the screen is included in a rear projection system.

2. In a projection screen, a sheet-like body of translucent material formed principally from gel- 25 atine and glycerine, and a sheet of uniform knit fabric incorporated in said translucent material on one surface thereof, said translucent material and said sheet of knit fabric cooperating to form a screen properly light-diffusive for rear projec- 30 tion practice, a substantial amount of light passing through said knit fabric and the translucent material when the screen is included in a rear projection system.

DAVID F. NEWMAN. 35
